UNITED STATES PATENT OFFICE

LEE DE FOREST, OF NEW YORK, N. Y., ASSIGNOR TO GENERAL TALKING PICTURES CORPORATION, OF NEW YORK, N. Y., A CORPORATION OF DELAWARE

MICROPHONE

Application filed October 2, 1929. Serial No. 396,642.

This invention relates in general to microphone pick-up devices for translating sound waves into varying electrical currents.

One of the objects of the invention is to obtain a microphone device which is at once small, free from "carbon noises", sensitive and not subject to the difficulties normally encountered in securing and maintaining perfect insulation between electrodes as is frequently the case with microphones of the carbon or electrostatic types.

Another object of this invention involves a microphone having an incandescent cathode and a movable anode responsive to sound waves.

Another object of this invention is to provide a microphone of the above type in which the cathode operates either in a vacuum or a gaseous atmosphere either above or below atmospheric pressure.

A still further object of this invention is to provide a microphone which possesses a lower impedance than impedance of an electrostatic microphone.

Other objects of this invention involve features of construction, gases employed as well as pressures, and other characteristics, all as will be described in greater detail below.

This invention resides substantially in the combination, construction, arrangement and relative location of parts all as will be described in further detail below.

Referring to the drawings

Figure 1 is a longitudinal cross-sectional view through one form of microphone employing the principles of this invention;

Fig. 2 is an end elevational view of this device;

Fig. 3 is a plan view of a modified form of cathode;

Fig. 4 is a side elevational view of the modified cathode with some parts in cross-section;

Fig. 5 is another form of microphone operating at greater than atmospheric pressure;

Fig. 6 illustrates still another form operating below atmospheric pressure;

Fig. 7 illustrates still another form of the

device operating below atmospheric pressure with a modified form of anode;

Fig. 8 is a cross-sectional view taken on the line 8—8 of Fig. 7.

As is well known the many forms of microphones now in use have various undesirable characteristics peculiar to each type. For example, the carbon microphone and the electrostatic microphone are sources of undesirable noises which reduce their efficiency of operation; the electrostatic type whose undesirable noises are in part due to improper insulation in their construction, and in the carbon microphone due to the presence of the high resistance carbon contacts. The microphone of this invention possesses a lower impedance than those generally used and, therefore, permits the use of a long cable between it and the device to which it is connected, which is not true of a microphone of electrostatic type, for instance, it does not operate well with a long cable connection such as is normally required, for example, in making talking motion pictures. These known forms of microphones, particularly the electrostatic types, are seriously affected by moisture conditions. The device of this invention is not so affected. The microphone on this invention is also particularly adapted for small constructions which is highly desirable in some uses.

For a better understanding of the invention and its advantages reference will be made to the drawings. In general the microphone of this invention may be said to be of the two-electrode vacuum tube type. The form of a device shown in Figure 1 comprises a metal cylinder 1 having a chamfered edge to which is welded the glass member 2 at the joint indicated at 2 to form a hermetic seal. In accordance with present welding practice the tube 1 is preferably of copper. By reducing the edge of the tube to make it thin the glass portion may be welded thereto in a manner now well known in the welding art. The glass portion 3 is provided with a re-entrant stem or tube 4 which is pressed together at the point 5 while hot to hermetically seal the tube at the point where the wires enter the vessel. The glass portion of the container

may be evacuated and sealed as at the points 6. The end of the tube 1 is closed by the metal cap 7 which is of thin material and forms a hermetic seal with the tube 1. Supported on 5 stiff wires 9 is a cathode 8 adapted to be heated to incandescence and preferably coated with an electronically active oxide coating. The wires 9 are connected to the supporting wires 10 which are sealed in the brace 5 and 10 to which are connected the lead wires 12. The cap 7 forms the anode of the device and may be made of thin copper, nickel, tantalum, duraluminum, or other suitable material pressed in the form of a cap. The wires 15 12 are connected across the variable resistance 13 to the current source 14 which is used to energize the cathode 8. The casing 1 is provided with a binding post 18 which is connected by a wire to one terminal of the primary 20 of a suitable transformer. The other terminal of the primary is connected through the current source 16 by wire 15 to one of the wires 12. The secondary 19 of the transformer is connected by the wires 20 to 25 any device to be actuated by the currents produced by the microphone, such as the input of an amplifier. The tube 4 is shown by this form of the device as extending beyond the brace 5 to help to support the cathode 8 and 30 its supporting wires 9. The complete vessel formed by the tube 1, glass member 3 and cap 7 may be exhausted preferably to a high degree of vacuum and sealed off. The device will, of course, operate when exhausted even 35 to a low degree. In certain cases it is preferable to employ some gas pressure other than air such as that provided by placing a globule of mercury within the container and exhausting it to the pressure of mercury 40 vapor. In addition to or in lieu of the mercury one of the noble gases such as argon, krypton and zenon, either pure or in any desired mixture thereof may be employed. Although the mercury tends in time to become 45 amalgamated with the copper tube the device still retains the qualities of a mercury vapor device. When the pressure within the device is below atmospheric pressure the thin diaphragm or anode 7 tends to bend inwardly 50 into a slightly concave form and puts the diaphragm under considerable tension. For good results the diaphragm is initially secured to the tube 1 under tension which tension is enhanced by the atmospheric pressure 55 sure thereon. This tension in the diaphragm materially reduces the natural period of vibration. In one desirable form the period of vibration of the diaphragm is well above one six thousandths of a second. In preferable form the cathode 8 is placed close behind the anode 7 at a distance of the order of one-sixteenth of an inch.

When sound waves are directed against the diaphragm they impart their vibrations thereto to alternately move the diaphragm

closer to and further from the cathode member thereby periodically altering the impedance of the device by and in accordance with the impinging sound waves. This action results in corresponding linear changes in the 70 electronic or ionic currents passing between the cathode and the anode. These electronic currents passing through the primary of the transformer are induced into the secondary 75 and then delivered to any device to be actuated thereby such as a multi-stage vacuum tube amplifier.

Instead of making the cathode in the form of a straight filament as shown in Figure 1 it may be made in the form of a spiral as 80 shown at 8a in Figs. 3 and 4. To prevent sagging of the spiral it may be supported on the disc 21 of insulating material such as mica. The mica disc may be supported from the brace 5 by means of the support wires 9 85 and additional support wire such as the wire 22. It is, of course, apparent that the cathode may be made in many forms without departing from this invention.

An important advantage of this construction of microphone is that it may be made extremely small. Thus its overall dimensions may be of the order of one inch across and two to three inches in length. Such a small microphone may be readily concealed 95 and is hence very well adapted for use in the making of talking motion pictures since it may be easily located close to the person speaking without it being observable in the 100 picture when thrown on the screen.

In the forms of the device shown in Figs. 5 and 6 the diaphragm 7 is made of rubber or rubberized fabric instead of metal and hermetically sealed to the tube 1. The form shown in Fig. 5 is intended to operate at 105 greater than atmospheric pressure and the tube 23 connected thereto to the valve 24 is employed to supply air or other gases alone or in combination at greater than atmospheric pressure to the device. In this case the diaphragm will convex outwardly. In the form of device shown in Fig. 6 the device is operated below atmospheric pressure and, as a result, the diaphragm will convex inwardly. Since a diaphragm of this type 110 might permit leakage in time the tube 23 which contains valve 24 is provided to correct the pressure condition within the device from time to time as it becomes necessary. In the case of a diaphragm of this nature its inner surface must be metallized to provide a conducting surface which will, of course, be in contact with the tube 1 to which one connection is made. Instead of metallizing the inner surface of the diaphragm the construction shown in Figs. 7 and 8 may be employed. In this case the anode comprises a supporting metallic ring 25 for a mesh 28. The anode is supported by the wires 26 and 27 from the stem 5 and a lead extends through the stem 115

for the anode connection. In the operation of the forms of device shown in Figs. 5 to 8 inclusive, the vibration of the flexible diaphragm in accordance with impinging sound waves produces alternate compression and a rarefaction of the gas within the chamber regardless of its pressure relative to the atmosphere. These changes of pressure within the device control the amount of ionic current

10 passing from the cathode to the anode and hence the impedance of the device.

15 It will be apparent from the foregoing disclosure that I have embodied certain principles of construction and operation in a new form of microphone device which principles may be embodied in other physical forms without departing from the spirit and scope of this invention. I do not, therefore, desire to be strictly limited to the form of disclosure 20 given for purposes of illustration but rather to the spirit and scope of the appended claims.

What I seek to secure by United States Letters Patent is:

25 1. A microphone device of the type described, comprising a glass portion and a metal portion hermetically sealed together, a conducting flexible portion hermetically sealed to the metal portion to form an anode 30 and a cathode within said vessel supported adjacent the flexible portion, said vessel being exhausted.

35 2. A microphone device of the type described, comprising a glass portion and a metal portion hermetically sealed together, a conducting flexible portion hermetically sealed to the metal portion to form an anode and a cathode within said vessel supported adjacent the flexible portion, said vessel containing a mixture of gases.

40 3. A microphone device of the type described, comprising a metal portion and a glass portion hermetically sealed together, said glass portion having a reentrant stem, a 45 flexible diaphragm hermetically sealed to the metal portion to form a closed vessel and a cathode supported on said reentrant stem adjacent said flexible diaphragm, said flexible diaphragm acting as a sound responsive 50 anode with respect to said cathode.

45 4. A microphone device of the type described, comprising a metal portion and a glass portion hermetically sealed together, said glass portion having a reentrant stem, a 55 flexible diaphragm hermetically sealed to the metal portion to form a closed vessel, a cathode supported on said reentrant stem adjacent said flexible diaphragm, said flexible diaphragm acting as a sound responsive 60 anode with respect to said cathode, current leads extending through said reentrant stem for said cathode, and means connected to said leads for energizing said cathode.

65 5. A microphone device of the type described comprising an exhausted vessel hav-

ing a portion thereof of flexible non-conducting material mounted under tension and having its surface exposed to the interior of the vessel metallized, said diaphragm forming an anode, and a hot cathode electrode within 70 said vessel.

6. In a microphone device of the type described the combination comprising an exhausted vessel having a portion of its wall made up of a rubber diaphragm, said diaphragm being metallized on its surface exposed to the interior of the vessel to provide an anode and a cathode within said vessel mounted adjacent the anode.

In testimony whereof I have hereunto set 80 my hand on this 30th day of Sept., A. D. 1929.
